Primary Examiner — Jennifer Rivard*Assistant Examiner* — April Rivas(57) **CLAIM**

The ornamental design for luggage, as shown and described.

DESCRIPTION

FIG. 1 is a perspective view from the front and left side of the luggage showing my new design;

FIG. 2 is an elevational view of the front of the present invention;

FIG. 3 is an elevational view of the back of the present invention;

FIG. 4 is an elevational view of the left side of the present invention;

FIG. 5 is an elevational view of the right side of the present invention;

FIG. 6 is a plan view of the top of the present invention;

FIG. 7 is a plan view of the bottom of the present invention;

FIG. 8 is a perspective view from the front and the right side of the present invention; and,

FIG. 9 is a perspective view of the present invention in a state of use, showing it in an opened configuration with a garment bag and other clothes placed inside the luggage.

The broken lines in FIG. 9 illustrating the garment bag and clothing represent environment. The remaining broken lines illustrate portions of the luggage. All of the broken lines form no part of the claimed design.
